TENNIS BALL SERVER

John P. Garver, Poland, Ohio

Application April 25, 1958, Serial No. 731,016

3 Claims. (Cl. 124—11)

This invention relates to a tennis ball server and more particularly to a device that will serve a tennis ball and impart a desirable spin thereto and closely simulate the service of a tennis player.

The principal object of the invention is the provision of a device that accumulates air under pressure and releases it in large volume instantaneously to eject a tennis ball from a barrel communicating with the device.

A further object of the invention is the provision of a tennis ball server incorporating a piston like closure controlling a passageway between an accumulator and a ball discharging barrel.

A still further object of the invention is the provision of a tennis ball server comprising an accumulator and a discharge barrel and a differential valve mechanism controlling communication between said accumulator and said barrel.

The tennis ball server disclosed herein comprises a device which will effectively serve a tennis ball and which accomplishes such service by releasing a substantial volume of compressed air under relative low pressure, the air releasing means comprising a differential valve and a trigger member for actuating the same so that instantaneous opening of said differential valve is insured.

The distance of the flight of the ball served is controlled by the air pressure and the direction of the flight of the ball served is controlled by the position of the device while the spin imparted the ball is controlled by a strip of flexible material which is positioned in the barrel of said device.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure which do not constitute departures from the spirit and scope of the invention.

The invention is illustrated in the accompanying drawing, wherein:

Figure 1 is a vertical section through the tennis ball serving device.

Figure 2 is a vertical section on line 2—2 of Figure 1.

Figure 3 is a vertical section on line 3—3 of Figure 1.

By referring to the drawing and Figure 1 in particular it will be seen that the tennis ball server comprises a cylindrical body 10 which has a head 11 secured thereto at one end, the head 11 being apertured centrally thereof and supporting a barrel 12 in axial alignment with said aperture.

An inwardly projecting relatively sharp annular ridge

2

13 is formed on the head 11 about the aperture therein. The opposite end of the cylindrical body 10 has a secondary head 14 secured thereto preferably in a movable manner as by means of a plurality of fasteners 15.

5 The secondary head 14 has a central aperture therein and a tubular extension 16 is secured thereto about said aperture. Said tubular member 16 is provided with an end closure 17.

A piston 18 is mounted on one end of a piston rod 19 and in spaced relation to a secondary piston 20 also positioned on said piston rod 19. The secondary piston 20 is positioned within the tubular member 16 for reciprocal movement therein.

The piston 18 is supported in axial alignment with the aperture in the head 11 by means of a plurality of guide rods 21—21 which are secured at their ends at the head 11 and extend inwardly therefrom in spaced parallel relation to one another.

The piston rod 19 extends outwardly beyond the closure 17 through which it is slidably positioned and terminates with its enlarged outward end 22 in spaced relation to the closure 17.

A trigger member 23 is slidably engaged on said piston rod 19 between said closure 17 and said end 22 so that it may be moved forcibly against said end 22 and thereby impart movement to the piston rod 19, the piston 18 and the secondary piston 20. Such movement as is imparted to the piston rod 19 is rapid and results in the rapid movement of the piston 18 away from the annular ridge 13. The compressed air accumulated in the cylindrical body 10 is therefore capable of flowing instantaneously in large volume into the barrel 12. The rapid movement of the piston 18 is insured by the secondary piston 20 which is only slightly smaller in area than the piston 18 so that only a relatively small amount of air pressure need be overcome by the trigger action as will be understood by those skilled in the art and familiar with the principles of differential air pressures and the resulting characteristics thereof.

40 The face of the piston 18 is provided with a sealing gasket 24 and a sealing gasket 25 is positioned between the cylindrical body 10 and the secondary head 14. Compressed air is introduced into the cylindrical body 10 through an inlet orifice 26 from a suitable source, not shown.

The barrel 12 as an annular band of fabric material, preferably pile fabric material 27, thereabout forming a partial liner adjacent the inner end of the barrel 12 so that balls of various sizes may be accommodated and effectively served by the device.

50 A strip of fabric 28 is positioned in the barrel 12 longitudinally thereof and secured thereto adjacent the annular band of fabric 27. When the ball indicated by the letter "B" in Figures 1 and 3 is served, the presence of the cloth strip 28 imparts desirable spin to the ball.

The device is provided with a supporting stand 29 preferably incorporating an adjustable universal joint 30 and a base 31.

60 It will thus be seen that a tennis ball serving device has been disclosed which meets the several objects of the invention and having thus described my invention, what I claim is:

1. A tennis ball serving device comprising an accumulator, a barrel in communication with said accumulator, a piston valve between said accumulator and said barrel, a cylinder in communication with said accumulator, a

piston rod extending from said piston valve through said cylinder and exteriorly thereof, a secondary piston on said piston rod and positioned in said cylinder, a trigger member slidably engaged on said piston rod exteriorly of said cylinder arranged to engage the outermost end of said piston rod to move the same and said piston valve and secondary piston thereon and a source of air pressure in communication with said accumulator.

2. The tennis ball server set forth in claim 1 and wherein guide rods positioned in said accumulator position and guide said piston valve. 10

3. The tennis ball server set forth in claim 1 and where-

5
4
in the area of said secondary piston is less than the area of said piston valve.
